INSULATING MATERIAL

Application filed March 23, 1928. Serial No. 264,129.

This invention relates to insulation of the cellular gypsum type. Insulation of this type is supplied in the form of a powder which is mixed with a predetermined amount 5 of water and allowed to set in order to form a solid mass. Prior to the setting the greater part of the added moisture combines with the powder, and gas is produced which forms dispersed cells throughout the mass while 10 causing a large increase in volume. The material hardens within a period of a few minutes. The hardened mass will not withstand severe crushing forces but has high insulating value and may readily be cut into 15 desired shapes. Heretofore where such insulation has been used in the construction of buildings or the like it has been the practice to fill in the space between the studding, joists or other framework with a slurry-like 20 mixture of the powdered composition and water. Obviously this practice necessitates the erection of a complete form for a wall comprising an outer sheathing or shell and a spaced, inner shell or falsework, and necessi- 25 tates moisture tight ceilings where a floor or ceiling is to be insulated. Waste of material often results because the mass of insulation is unnecessarily thick. Further in many 30 cases the moisture required in excess of that which will combine with the powder is objectionable because of the difficulties attending the subsequent drying. This excess is normally between eight and twelve per cent of the water added to make the cellular com- 35 position. Notwithstanding the difficulties attendant upon securing a tight form and in drying excess moisture after the composition has set, this type of insulation is in wide demand for building purposes because of its 40 light weight, high insulating and fire proof qualities and capacity to expand and set with resultant sealing of all connected spaces which would otherwise be left open.

It is the object of this invention to eliminate the objectionable features above pointed out while retaining the salient good qualities of such insulation.

More particularly, it is our object to provide insulation in the form of protected 50 panels, adapted to be secured between the

frame members of buildings and containing an integral and previously set and dried body of cellular gypsum composition, the panels being formed to permit sealing of the sides of the same in place by grouting consisting of a relatively small amount of the same composition mixed wet and poured after the panel is in place in the wall or floor of a building. 55

Our invention also includes a novel and efficient method of making solid integral panels of such insulation in a protecting envelope adapted to be shipped for installation between the frame members of buildings. 60

The invention will be best understood by reference to the accompanying drawings in which Figure 1 is a perspective view of a unit or panel of our improved insulating material; Fig. 2 is a horizontal section through a partially erected wall showing the arrangement of the insulation therein; Fig. 3 is a vertical section through a portion of a ceiling with our insulation installed; Fig. 4 is a perspective view of a suitable mold for forming the panels, with the cover open 70 and Fig. 5 is a vertical section taken on the line 5—5 of Fig. 4, but with the mold cover closed. 75

In the drawings we have used the numeral 6 to indicate a hardened, integral body of cellular gypsum composition which is enclosed to form a unit or panel by an envelope 7. Paper board on account of its cheapness is preferred for the construction of the envelope 7 although any suitable sheet material 80 may be used. We have found that chip board of from 15 to 20 point thickness has sufficient strength and flexibility to meet the requirements of the envelope 7. The envelope is creased and folded to form a tubular structure covering all of the longitudinal sides of the panel. The panel is quadrilateral in cross section having parallel sides 8 and 9 with edges 10 converging from the side 8 to the side 9 and forming equal oblique angles with said sides. At the longitudinal edges of the side 8 the envelope projects and is folded back upon itself to form relatively 90 flexible flanges 11 which normally project in continuation of the side 8. The cellular 95

gypsum composition 6 which completely fills the envelope 7 adheres to the inner surface of the envelope when formed as hereinafter described.

5 In forming the envelope, a rectangular sheet of suitable paper board or other foldable sheet material is creased to form a tubular structure with overlapping edges 12 extending along one side. The tube thus formed is of uniform size and shape in cross section throughout its length and may be made of any desired length depending upon the size of the panel desired. Obviously the width and thickness of the panels may also be 10 varied between wide limits but where they are to fit between the studding of a building with the studding at the standard spacing of sixteen inches between centers, the panel is made 14 $\frac{1}{4}$ inches across the side 8 and with 15 the flanges 11 about $\frac{1}{2}$ inch in width, thus making the panel 15 $\frac{1}{4}$ inches over all in width. The side 9 may be made about 12 $\frac{1}{4}$ inches in width and for most installations we prefer a thickness of panel of about three 20 inches.

25 In Fig. 2 we have illustrated the method of installing our invention between the studding of a building. As here illustrated the members 13 are the studding of a building. 30 The outer shell of a wall is indicated by the numeral 14. Assuming that the members 13 and the shell 14 or sheathing has been erected, a panel of our insulating material may be quickly and easily secured between each pair 35 of the members 13. Thus a panel, of say 6 to 10 feet in length, may be pressed between a pair of the members 13 by inserting the narrow side 9 first and forcing the flanges 11 to bend back by wedge action against the opposed faces of the members 13. As some 40 force is required to bend the flanges 11 we prefer to apply a rigid board or other support 15 to the outer surface of the side 8 when inserting a panel. The operator merely 45 presses upon the support 15 in forcing the panel into place. When the panel has been inserted it will be evident that triangular spaces 16 are left at each longitudinal edge thereof. In order to fill this space and 50 securely hold the panel in place we now insert grouting 17. This grouting is preferably formed by mixing suitable proportions of dry gypsum powder and water and pouring the mixture into the triangular spaces 16. This 55 composition immediately sets after expanding and fills all connected openings. As the amount of grouting is small compared with the insulation 6, previously dried, there is a 60 very small excess of moisture to be disposed of after the grouting has set. We have found that this excess is quickly absorbed by the surrounding structure and that the panels so secured in place have excellent insulating qualities. The panels may be fitted

end to end to fill in the entire space between frame members.

70 The flanges 11 perform a number of important functions. Notwithstanding the fact that the spacing of the studding or other frame members varies somewhat due to errors and unavoidable irregularities, the flexible and resilient flanges 11 insure firm contact with the studding throughout their length. Thus these flanges retain the insulating panels in place until the grouting 17 75 can be poured and adjust themselves so as to conform to the frame members and insure the retention of the grouting 17 when it is poured in liquid state into the triangular spaces 16.

80 Fig. 3 illustrates how our improved insulation may be used in a ceiling or floor. As here shown the numeral 19 indicates a horizontal support which may consist of false-work or a permanent part of the building and the joists are indicated by the numeral 20. The broader sides 8 of the panels are preferably placed adjacent to the support 19, the panels being forced into place by bending the flanges 11 against the opposed faces of the joists 20. Triangular bars of grouting 21 are 85 finally cast in situ by pouring the fluid mixture of gypsum composition and water between the joists 20 and the longitudinal edges 10 of the panels. As above pointed out the flanges 11 resiliently conform to the joists 20 to insure retention of the grouting 21 when it is poured. The insulation may be 90 applied to an old ceiling where there is danger of staining or otherwise injuring the decorated surface. For such use it will be seen that our invention has marked advantages over the old method of pouring a large amount of the composition upon the backing 95 for the ceiling because the moist grouting is separated from the ceiling by the flanges 11. Even if a small amount of the grouting should leak past these flanges we 100 have found that this is insufficient to injure the ceiling in any way because the excess of moisture is quickly absorbed.

105 A suitable mold for forming our insulation is shown in Figs. 4 and 5. As here shown we provide a pair of parallel and inclined side members 22 adapted to support the edges 10 of the panels and a removable bed 23 also supported in inclined position and adapted to support the side 9 of the insulating panel. Longitudinal brace members 24 upon the bottom of the bed 23 give rigidity to the same while suitable legs 25 and 26 support the members 22 in inclined position. To the inner edges of these legs 25 and 26 are secured longitudinal bars 27 for removably supporting the bed 23. Upon the top of the side bars 22 are secured furring strips 28 extending longitudinally thereof in parallel relation to each other. These strips are adapted to receive between them a cover 29 which is pivot- 110 115 120 125 130

ally secured at its lower end by hinges to a transverse member 31. This member 31 is rigidly secured across the ends of the members 22 and forms a closure for the lower end 5 of the mold.

To form a panel in the mold above described an envelope 7 creased and folded to final form is inserted as indicated in Figs. 4 and 5 between the members 22 and with the 10 flanges 11 of the envelope supported upon the top of said members. The cover 29 is now closed as indicated in Fig. 5 so as to retain the flanges 11 in collapsed form and to confine or hold down the upper surface of the 15 envelope 7. A suitable wet mixture of gypsum composition is now poured into the open upper end of the envelope 7. Within a few minutes the composition sets so that it is self sustaining and the cover 29 is opened to permit the withdrawal of the molded panel with 20 its envelope. The panel is now removed together with the supporting bed 23 and placed in an oven where it is dried. When dry the panels are sufficiently reinforced by the envelope 7 to permit shipping and handling 25 without destruction.

Having described our invention what we claim is new and desire to protect by Letters Patent is:

30 1. An insulating material adapted to be inserted between frame members of a building comprising, a long and relatively narrow panel of cellular gypsum composition or the like adapted to be inserted between frame 35 members of a building, an envelope of foldable sheet material adapted to be inserted with said panel between said frame members and covering the longitudinal faces and side edges of said panel and a flexible flange extending along and projecting from the outer 40 extremity of a longitudinal edge of said panel, said flange being arranged to make contact with one of the opposed faces of said members.

45 2. The insulating material specified in claim 1 in which the outer extremities of both longitudinal edges of said envelope are formed with resilient flanges adapted to conform to the opposed faces of frame members 50 when inserting between said members.

55 3. An insulating material adapted to be inserted between frame members of a building comprising, a long and relatively narrow panel of cellular gypsum composition or the like having beveled longitudinal side edges, an envelope of foldable sheet material covering the longitudinal faces and side edges of said panel and a flexible flange extending along a longitudinal edge of said panel and 60 projecting outward from the extreme outer corner of at least one of said beveled edges, said panel being formed to fit between frame members of a building with said flange making resilient contact with one of the opposed 65 faces of said members.

4. An insulating material adapted to be inserted between frame members of a building comprising, a long and relatively narrow panel of cellular gypsum composition or the like having portions of its longitudinal side edges offset inward from the outer extremities thereof, an envelope of foldable sheet material covering the longitudinal faces and side edges of said panel and formed with a flexible flange projecting from the outer extremity of at least one of said side edges, said panel being adapted to fit between said frame members of a building with said offset portions and flanges forming longitudinal receptacles for grouting and a filling of grouting 70 in said receptacles. 75

5. An article of manufacture comprising, a body of insulating material having parallel faces and a longitudinal side edge forming an acute angle with one of said faces and a flexible flange projecting from said edge at its junction with said last mentioned face and extending longitudinally of said body. 80

6. An article of manufacture comprising, a body of insulating material substantially enclosed with an envelope of foldable sheet material and having portions of a longitudinal side edge offset inward from the outer extremity of said edge and a flexible flange projecting outward from the outer extremity 90 of said side edge. 95

In testimony whereof, we have hereunto signed our names to this specification.
